J. E. CURTI,
LIGHTNING ROD STRUCTURE,
APPLICATION FILED APR. 3, 1916.

1,214,652.

Patented Feb. 6, 1917.

UNITED STATES PATENT OFFICE.

JOHN E. CURTI, OF OMAHA, NEBRASKA.

LIGHTNING-ROD STRUCTURE.

1,214,652.

Specification of Letters Patent.

Patented Feb. 6, 1917.

Application filed April 3, 1916. Serial No. 88,610.

To all whom it may concern:

Be it known that I, JOHN E. CURTI, a citizen of the United States, residing at Omaha, in the county of Douglas and State 5 of Nebraska, have invented certain new and useful Improvements in Lightning-Rod Structures, of which the following is a specification.

This invention relates to a lightning rod 10 structure, and has for its principal object to provide a coupling for connecting the standard with the horizontal cable, which will be of simple construction, so that it may be economically manufactured, may be conveniently applied, and will be effective in 15 use for firmly connecting the parts.

The invention also has reference to the provision of a standard having a bifurcated terminal to form an outwardly divergent 20 base which operates to advantage for bracing or supporting the standard, and for conducting electrical charges from the standard to the cable.

With the foregoing objects in view the 25 invention presents a novel construction, combination and arrangement of parts as described herein and claimed, and as illustrated in the accompanying drawing, wherein—

30 Figure 1 is a view in side elevation showing the coupling applied to a standard and cable. Fig. 2 shows a side view of the standard mounted on the cable, both being broken away, a housing or jacket for connecting 35 these parts being shown in section, with its flanges extended. Fig. 3 is a sectional view of the cable on line 3 3 of Fig. 1. Fig. 4 is a view similar to that shown in Fig. 3, the flanges being extended. Fig. 5 is a plan 40 view of a plate employed to form a jacket or housing for connecting the cable and standard. Fig. 6 is an enlarged detail showing a modified form for the secondary prongs.

45 Referring now to the drawing for a more particular description, numeral 6 indicates a standard used as an electrical conductor and which is disposed at right angles to the cable 7 which is disposed horizontally and 50 also used as an electrical conductor. The standard is of tubular form and is constructed of sheet metal.

For purposes of the invention, the lower 55 part of the tubular standard is incised longitudinally and flattened to provide two prongs 8 and 9, each prong being incised

longitudinally at its end to provide a foot-piece or pair of secondary prongs 10 and 11 for a seating stridly upon the cable 7. The prongs 10 and 11 may be seated upon the upper part of the cable, or as shown in Fig. 6, may nearly circumscribe said cable. The prongs 8 and 9 are disposed outwardly divergent so that the secondary prongs for each of the first named prongs are located 60 a considerable distance from each other, comparatively, and the inclination of the prongs 8 and 9 is uniform with reference to the axis of the standard. It will be appreciated by those conversant with the art that the divergent prongs 8 and 9 discharge the function of resisting to great advantage all 65 stresses directed in line with the cable and transversely of the standard, as for instance, the action of high winds or accidentally incurred stresses, an important second function discharged by these prongs being that an electrical current will be more readily conducted on said inclined prongs, from the standard to the cable, than it would at a 70 right angle.

To provide a holder which may be constructed at a limited expense and which may be readily applied, the elongated, metallic plate 12 is employed. It is formed outwardly convergent toward its ends, and is provided with apertures 13. It is bent intermediate its ends to provide a loop 14 to embrace the secondary prongs 10 and 11 and the lower side of the cable, and to provide 75 a pair of side plates 15 and 16, each of the side plates having flanges 17 and recesses 18 arranged in pairs, a flange 17 of each pair being disposed opposite to a recess 18.

In operation, after the standard has been 80 disposed with its prongs 10 and 11 engaging the cable, the plate 12, having been bent to form the clamping device as described, is applied in the manner above mentioned, the two convergent side plates of the device 85 being disposed at the sides and in engagement with the flat prongs 8 and 9, and the flanges 17 may be then bent transversely, by use of a pair of pincers or a similar tool, the flanges 17 of each side plate being disposed in an adjacent recess 18 of a side plate, as shown in Figs. 1 and 3, afterward a stove bolt 19 or similar keeper is passed through the apertures 13 as an additional means for securing the ends of the side 90 plates.

It will be understood that the important

feature in the use of the divergent prongs 8 and 9, aside from the fact that they are disposed in line with the cable for resisting stresses to advantage, is that they are disposed inclinedly from the standard to the cable to facilitate conducting an electric current; and while I have shown secondary prongs 10 and 11 for engaging the cable, I do not wish to be understood as limiting myself in this respect, and I may dispense with the secondary prongs in some instances. Also I may employ any suitable material for constructing the parts and I may change the size and proportion of said parts.

Having fully described construction, what I claim and desire to secure by Letters Patent is,—

1. In a lightning rod structure, a horizontal cable, a metallic, tubular standard flattened adjacent its lower end and having said flattened portion incised longitudinally to provide prongs and secondary prongs at the terminals of the first named prongs, said standard being disposed vertically with its secondary prongs in engagement with the cable, an elongated, metallic housing plate bent midway between its ends to provide a part for embracing the cable and secondary prongs and having opposed, convergent ends for embracing the first named prongs, and a plurality of fastening devices at the opposed edges of the convergent ends of said housing plate in engagement with the first named prongs.

2. In a lightning rod structure, the combination with a cable and a metallic tubular standard having terminal, divergent prongs disposed in line with and engaging the cable, of a housing plate bent midway between its ends to provide a part for embracing the cable and having opposed, convergent ends for embracing the prongs, and a plurality of fastening devices at the opposed edges of the convergent ends of said housing plate in engagement with said prongs.

3. In a lightning rod structure, a cable, a metallic-tubular member having outwardly divergent prongs at one of its ends and disposed transversely of the cable its prongs being in line with and engaging said cable, and a metallic, elongated plate hav-

ing convergent end-portions provided with recesses and flanges, said plate being bent midway between its ends to provide a loop for engaging the cable and to provide a pair of side members for engaging the prongs, the flanges of each side member being adapted to be disposed in the recesses of the other side member.

4. In a lightning rod structure, a horizontal cable, a metallic, tubular member incised longitudinally to provide a pair of outwardly divergent prongs and secondary prongs at the terminals of the first named prongs, said tubular member being disposed transversely of the cable, its secondary prongs being disposed stridly upon and its first named prongs being disposed in line with said cable, a metallic, elongated plate having convergent end-portions provided with recesses and flanges, said plate being bent midway between its ends to provide a loop for engaging the cable and secondary prongs and to provide a pair of side members for engaging the first named prongs, the flanges of a side member engaging in the recesses of the other side member, and a keeper traversing the side members of said elongated plate.

5. In a lightning rod structure, a horizontal cable, a metallic, tubular member flattened adjacent to its lower end and having said flattened portion incised longitudinally to provide a pair of outwardly divergent prongs and secondary prongs at the terminals of the first named prongs, and an elongated plate formed convergent at its ends and provided with a plurality of flanges and recesses, said plate being bent to provide a pair of side members for embracing the cable and prongs after the tubular member has been disposed vertically with its secondary prongs in engagement with the cable, the flanges of one side member engaging in the recesses of the other side member.

In testimony whereof, I have affixed my signature in presence of two witnesses.

JOHN E. CURTI.
